(57) **CLAIM**

The ornamental design for a cargo hook, as shown and described.

DESCRIPTION

FIG. 1 is a perspective view of a cargo hook

FIG. 2 is a front view of the cargo hook of the present invention

FIG. 3 is a rear view of the cargo hook of the present invention

FIG. 4 is a first side view of the cargo hook of the present invention

FIG. 5 is a second side view of the cargo hook of the present invention

FIG. 6 is a top view of the cargo hook of the present invention; and,

FIG. 7 is a bottom view of the cargo hook of the present invention.

The cargo hook is shown with symbolic breaks in its length. The appearance of any portion of the article between the break lines forms no part of the claimed design.
